Malcolm E. Cooper, Dorset, Vt., assignor to J. K. Adams Company, Inc., Dorset, Vt., a corporation of Vermont

Application April 10, 1953, Serial No. 24,451

Term of patent 14 years

(Cl. D11—1)

To all whom it may concern:

Be it known that I, Malcolm E. Cooper, a citizen of the United States and resident of Dorset, Vermont, have invented a new, original, and ornamental Design for a Kitchen Chopping Block, of which the following is a specification, reference being had to the accompanying drawing, forming a part hereof.

Fig. 1 is a perspective view of a kitchen chopping block, showing my new design.

Fig. 2 is a side elevation of the block viewed from the right in Fig. 1, and

Fig. 3 is an end elevation viewed from the left in Fig. 1.

The knife shown in phantom is for illustrative purposes only.

I claim:

The ornamental design for a kitchen chopping block, as shown and described.
